ATTORNEY

UNITED STATES PATENT OFFICE.

FREDERICK L. RE QUA, OF MILWAUKEE, WISCONSIN, ASSIGNOR TO THE CUTLER-HAMMER MFG. CO., OF MILWAUKEE, WISCONSIN, A CORPORATION OF WISCONSIN.

THERMALLY-CONTROLLED CIRCUIT INTERRUPTER.

Application filed May 9, 1921. Serial No. 468,127.

To all whom it may concern:

Be it known that I, FREDERICK L. RE QUA, a citizen of the United States, residing at Milwaukee, in the county of Milwaukee and State of Wisconsin, have invented new and useful Improvements in Thermally-Controlled Circuit Interrupters, of which the following is a full, clear, concise, and exact description, reference being had to the accompanying drawing, forming a part of this specification.

This invention relates to thermally controlled circuit interrupters and more particularly to those of the fluid contact type.

15 In a copending application of Erwin R. Stockle, filed February 14, 1920, Serial No. 358,601, is disclosed and claimed such a circuit interrupter adapted to be subjected to electro-thermic influence of a single circuit for response of the interrupter and also 20 adapted to reset automatically, and the present invention has among its objects that of providing such a circuit interrupter adapted to effect response thereof under electro-thermic influence of any one of a plurality of 25 circuits such, for example, as the individual phase lines of a polyphase circuit.

Other objects and advantages will hereinafter appear.

30 In the accompanying drawing wherein are illustrated certain of the forms which the invention may assume in practice,

Fig. 1 is a longitudinal sectional view thereof, certain typical circuit connections therefor being illustrated diagrammatically; while,

Figs. 2 and 3 are similar views illustrating slightly modified forms of circuit interrupter.

40 In the construction illustrated in Fig. 1, as in said copending application, a tube 5 of glass or other insulating material is provided terminally with solid electrodes 6 and 7 normally electrically connected by a quantity 8 of liquid conductive medium hereinafter designated as mercury, although obviously other substances may be employed, electro-thermic means being provided and adapted upon increase, above a given value, 45 of the current traversing the same to effect vaporization of an intermediate portion of the column of mercury for sudden expulsion of a portion of the liquid mercury from the region between said electrodes to thereby 50 interrupt circuit therebetween, the mercury

so expelled being received within a suitable reservoir located above the tube and in communication therewith as illustrated.

The tube 5 is preferably arranged in a vertical position as illustrated whereby following escape or condensation of the vaporization mercury, the displaced body of liquid mercury is adapted to flow back within the tube thereby re-establishing the interrupted circuit.

Said tube, throughout the major portion of its length is of such diameter that the column of mercury contained therein is too large to be intersected or electrically interrupted by any air or gas bubble which is 65 likely to become entrapped during such reflux of mercury within said tube thus tending to effect positiveness of the resetting action. Moreover the mercury column is constricted as illustrated at 9 to prevent 70 forcing of bubbles of any appreciable size past such constriction, whereas the electrode 6 is of a length sufficient to project inwardly beyond such constriction of the mercury column, thus insuring against defeat of the resetting action by possible entrapment of a larger bubble above such constriction. Said constriction also serves to promote positiveness and suddenness of the 75 response of the circuit interrupter in a manner more fully disclosed in said copending application but not important herein.

80 In addition to the foregoing features the instant device comprises the additional elements to be now described, rendering the 85 same responsive to electro-thermic conditions of any of a plurality of circuits.

To such end the column of mercury within the tube 5 is provided with one or more additional constricted portions such as that 90 indicated at 10, the total number of constricted portions preferably corresponding to the number of individual circuits to the electrical condition of which the device is 95 designed to be responsive. Further those portions of the mercury column located immediately below each of the constricted portions of such column are provided with individual heating means such as the coils 11 and 12 illustrated, said coils being connected 100 in the individual circuits adapted to influence response of the device.

105 Thus, upon predetermined rise in current traversing any of said coils, vaporization of the adjacent portion of the mercury col-

umn occurs for suddenly expelling from the tube the liquid mercury located thereabove, thereby interrupting circuit through the device, and upon escape from the tube or upon condensation of such vaporized mercury, the liquid mercury so expelled is adapted to flow back within the tube for automatic resetting of the device.

The aforescribed constriction of the column of mercury between the coils 11 and 12 prevents any appreciable circulation of mercury through such constriction whereby the temperatures of the bodies of mercury directly associated with the individual coils exert but a negligible influence upon one another, such restriction preventing heat exchange due to convection, whereas the heat absorbing casing 13 ordinarily employed to support the tube, similarly minimizes transfer of heat from either coil to the other by radiation.

It thus results that each coil is adapted to exert its own peculiar influence upon the mercury column without material influence by the action of the other coil, that is to say, the temperature at which response of the device occurs due to energization of one coil is not influenced to any material extent by any degree of heating due to action of the other coil less than the degree required to effect actual response.

If desired, the constricted portions of the mercury column other than the uppermost of such constrictions may be provided with solid conductive means such as the elements 14 and 15 of Figs. 2 and 3 respectively, thus insuring maintenance of electrical continuity through such constriction in the event of trapping of a large bubble of gas above such lower constriction.

The circuit connections illustrated in Fig. 1 are typical of those which may be employed for adapting the aforescribed interrupter to the control of a three phase motor 16 or the like. Obviously said connections are such that upon a given degree of overload in any phase of the motor circuit the interrupter is adapted to respond, de-energizing the closing winding of main switch 17 for interrupting the motor circuit, whereupon following the aforescribed automatic resetting of the interrupter the motor may be restarted by means of push button 18.

Obviously if desired the form of the device may be modified in various ways; thus the tube 5 might be constructed U-shaped, the upper portions thereof being provided with individual mercury reservoirs, both electrodes being similar to the electrodes 6 and the heating coils being similarly arranged with reference thereto.

What I claim as new and desire to secure by Letters Patent is.

65 1. In a circuit interrupter, the combina-

tion with a column of conductive liquid and electrodes to be connected thereby, of electro-thermic means subjecting said column to influence of a plurality of circuits for effecting interruption of electrical continuity of said column upon attainment of certain electrical conditions of any of said circuits, said column having means rendering the response thereof to influence of the electrical condition of one of said circuits substantially independent of influence of the condition of other of said circuits.

2. In a circuit interrupter the combination with a column of conductive liquid, of electro-thermic means for subjecting said liquid to fluid pressure of its own vapor for interruption of electrical continuity thereof, said means including elements subjected to influence selectively by different circuits.

3. In a circuit interrupter the combination with a column of conductive liquid, of electro-thermic means for subjecting said liquid to fluid pressure of its own vapor for interruption of electrical continuity thereof, said means including elements subjected to influence selectively by different circuits, and means to minimize the influence of each circuit upon the response due to influence of other of said circuits.

4. A thermally controlled circuit interrupter comprising a substantially vertical tube to contain a column of mercury, electrodes to be electrically connected by said mercury, means constricting the cross sectional area of said column at a plurality of points, a plurality of electro-thermic devices, having independent circuit connections, associated with said column at regions adjacent the respective constrictions thereof for interrupting electrical continuity of said column, certain of said constrictions serving substantially to limit the influence of individual electro-thermic devices to the portions of the column respectively associated therewith.

5. A thermally controlled circuit interrupter comprising a substantially vertical tube to contain a column of mercury, means associated with said tube to provide a reservoir thereabove and in communication therewith, electrodes to be electrically connected by said mercury, means constricting the cross sectional area of said column at a plurality of points, a plurality of electro-thermic devices, having independent circuit connections, associated with said column at regions adjacent the respective constrictions thereof for subjecting an intermediate portion of said column to fluid pressure of its own vapor to force liquid mercury from said tube into said reservoir to thereby effect sudden interrupting of circuit between said electrodes, certain of said constrictions serving to limit the influence of individual electro-thermic devices to the portions of the column

respectively associated therewith, said tube being of such internal diameter as to permit reflux of the expelled mercury for automatic resetting following escape from the tube or 5 condensation of the vaporized mercury.

6. In a circuit interrupter, the combination with a column of conductive liquid having a constricted portion and electrodes to be connected by said column of liquid in a 10 relation to shunt said restricted portion of the column of liquid, of electro-thermic means to subject said column to fluid pressure of its own vapor for interrupting electrical continuity thereof between said electrodes, said means including elements subjected to influence of electrical conditions of 15 different circuits respectively.

7. In a circuit interrupter, the combination with a column of conductive liquid hav-

ing a constricted portion and electrodes to 20 be connected by said column of liquid in a relation to shunt said restricted portion of the column of liquid, of electro-thermic means to subject said column to fluid pressure of its own vapor for interrupting electrical continuity thereof between said electrodes, said means including elements subjected to influence of electrical conditions of 25 different circuits respectively, said column having a further constricted portion located 30 within the region between said electrodes and serving to minimize the influence of each of said elements upon the response due to other of said elements.

In witness whereof, I have hereunto subscribed my name.

FREDERICK L. RE QUA.
